SHUTTLE CAR UNIT

William H. Chandlee, Jr., Southampton, and Norman W. Fesmire, Huntingdon Valley, Pa. (both $\frac{1}{2}$ The Budd Co., 2450 Hunting Park Ave., Philadelphia 32, Pa.)

Filed Sept. 28, 1962, Ser. No. 71,914

Term of patent 14 years

(Cl. D66—1)

FIG. 1 is a perspective view of a shuttle car unit embodying our new design;

FIG. 2 is a fragmentary side elevational view thereof;

FIG. 3 is a fragmentary top plan view thereof; and

FIG. 4 is an enlarged sectional view taken on lines 4—4 of FIG. 2.

The essential features of our new design reside in the portions shown in full lines in the drawing. The cross hatched areas on the side panels are intended to represent contrast.

We claim:

The ornamental design for a shuttle car unit, as shown and described.
